UNITED STATES PATENT OFFICE.

EDWIN O. KLEMM, OF DAYTON, OHIO, ASSIGNOR TO KLEMM MANUFACTURING COMPANY, OF FENTON, MICHIGAN, A CORPORATION.

CONTROL MECHANISM FOR GRAPHOPHONES.

1,417,748.

Specification of Letters Patent.

Patented May 30, 1922.

Application filed September 15, 1920. Serial No. 410,517.

To all whom it may concern:

Be it known that I, EDWIN O. KLEMM, a citizen of the United States, residing at Dayton, in the county of Montgomery and State of Ohio, have invented certain new and useful Improvements in Control Mechanism for Graphophones, of which the following is a specification.

This invention comprises an improved device for controlling the operation of graphophones of types most commonly in use today.

The primary object of the invention has been to devise provisions such that the starting and stopping of the graphophone is made a part of the function of the tone or reproducer arm. In other words I have so designed the stopping device, and parts intermediate of the said device and reproducer arm, that by proper manipulation of the latter the motor by which the record carrier or table is actuated may be caused to operate said carrier; another manipulation of said arm will cause an adjustment of the parts whereby a predetermination of the point on the record where stopping of reproduction will take place is obtained; and the customary movement or manipulation of the tone arm may be employed to carry it to the proper point for deposit on the record to commence reproduction in the usual manner. The stopping of reproduction may be predetermined to take place at the end of the record or at a point intermediate of the ends of the record and the peculiar means by which I accomplish the results above outlined are possessed of simplicity and require a comparatively small number of parts to enable the construction to be put into practical use.

40 In the accompanying drawings,

Figure 1 is a perspective view of a preferred embodiment of the invention.

Figure 2 is a sectional view, partly in elevation.

45 Figure 3 is a sort of diagrammatic view to show the peculiar movement of the reproducer arm when actuated by the controlling, starting and stopping of the record carrier.

The improvements of this invention represented a division of my application serial No. 310,910, filed July 15, 1919.

Describing these improvements specifically and referring particularly to the drawings, it will be observed that I utilize the tone arm 50 E carrying the reproducer F and of a common type at present in use. The arm E is

susceptible of up and down and lateral movements through the provision of the ball and socket connection E' with the base A of the machine. The base A is equipped with the usual motor B, adapted to drive the spindle C by which the record carrier D is supported as usual.

I utilize brake means consisting of the brake shoe 8 cooperative with the disc 1 of the governor 2.

The starting and stopping controlling device includes primarily a shaft 4, journaled in a plate 3, and provided with an arm 7 at one end, carrying the brake shoe 8. The opposite end of the shaft 4 is extended upwardly to form a detent arm 6, including the horizontal extension 6^a and the downward extension 6^b.

An extension 9 on the plate 3 is connected by a spring 10 with the detent arm 6 and normally tends to rock the shaft 3 to raise the parts 6^a and 6^b of the detent device, and thereby to engage the brake shoe 8 with the governor disc 1.

From the reproducer arm E, for cooperation with the detent means and brake above described, is a trip 13 having frictional rotative connection with the lower part of the arm E and formed with a downward bend 85 and lateral extension or trip arm 14. The part 14 is adapted to engage the parts 6^b and 6^a of the detent means.

With the foregoing understanding of the construction of the parts and their general relation, the following peculiar operations for controlling the stopping point and starting of the carrier D and the record thereon may be obtained. Assuming that the reproducer needle occupies a position at rest about 90 at the center of the record, and referring to Figure 3, to adjust the reproducer for stopping of the record at the end of the record track, the operator will grasp the reproducer arm E, elevate the same slightly and shift 100 the arm outwardly, say from A' to B' according to the diagrammatic illustration of Figure 3. In this way the member 14 of the trip 13 is caused to engage the part 6^b of the detent arm 6 effecting a proper adjustment of the trip 13 for a predetermined stopping point, in this instance, at the inner end of the record track. Thereafter the arm E is raised and caused to traverse a path something like that shown from B' to C' in Figure 3, the member 14 in this way being caused to depress the portion 6^a of the arm 6, in

such a manner as to disengage the brake shoe 8 from the governor disc 1. The operation of the carrier D is thus started by the motor when released in this manner. Thereafter the operator merely shifts the reproducer arm from the point C' to the point D' as designated in Figure 3, assuming the point D' to be the position at which the arm E should be deposited for commencement of reproduction of the record.

I contemplate that there may be two variations of the mode of operation just described. In the first place the adjustment of the reproducer arm E preliminarily to control the stopping point may be at any point to bring the needle to any point in the length of the record during the preliminary outward adjustment and before the raising movement characterized as B' to C' in Figure 3 commences. Again, the operator may of course, deposit the needle at any point in the length of the record for starting; he does not have to deposit it at the outer end of the track of the record.

Having thus described my invention what I claim as new is:

1. Graphophone mechanism comprising in combination, a record carrier and a reproducer to traverse a record on said carrier, driving mechanism for the carrier, stop means for the driving mechanism, including a brake member, an arm carrying the reproducer, a trip on the reproducer arm movable with and independently thereof, and a detent connected with the brake member to control the operativeness thereof, said detent embodying an arm having a portion to engage and cause movement of the trip relatively to the arm, and a second portion to engage the trip and to be restrained from movement by the trip, and spring means to move the detent arm when the restraining influence of the trip is removed therefrom.

2. In graphophone mechanism, the combination with a record carrier and reproducer arm having a reproducer to traverse a record upon said carrier, of a stopping device for the carrier, and instrumentalities intermediate the reproducer means and stopping device for adjusting the instrumentalities relatively to the reproducer to predetermine the point on the record when stoppage of reproduction will take place, and for actuating the stopping means to permit starting of the carrier.

3. In graphophone mechanism, the combination with a record carrier and reproducer arm having a reproducer to traverse a record upon said carrier, of a stopping device for the carrier, a trip on the arm and a controlling detent connected with the stopping means, the trip and detent being manually operable to coact with one another first for adjusting the trip relatively to the arm to predetermine the time when the stopping

means shall become effective for stopping; and second, to move the detent to release the stopping means to permit starting of the carrier for reproduction.

4. In graphophone mechanism, the combination with a record carrier and reproducer arm having a reproducer to traverse a record upon said carrier, of a stopping device for the carrier, a trip on the arm and a controlling detent connected with the stopping means, the trip and detent being manually operable by manipulation of the arm.

5. In graphophone mechanism, the combination with a record carrier and reproducer arm having a reproducer to traverse a record upon said carrier, of a stopping device for the carrier, a trip on the arm and a controlling detent connected with the stopping means, the trip and detent being manually operable by the arm to engage the trip with the detent so that the trip is temporarily held stationary while the arm moves, and to move the trip with the arm to engage and shift the detent to thereby release the stopping means to permit the carrier to operate.

6. In graphophone mechanism, the combination with a record carrier and reproducer arm having a reproducer to traverse a record upon said carrier, of a stopping device for the carrier, a trip on the arm and a controlling detent connected with the stopping means, the trip and detent being manually operable by the arm to engage the trip with the detent so that the trip is temporarily held stationary while the arm moves, to move the trip with the arm to engage and shift the detent to thereby release the stopping means to permit the carrier to operate, and to shift the arm to a position for commencement of reproduction of a record on the carrier.

7. In graphophone mechanism, the combination with a record carrier and reproducer arm having a reproducer to traverse a record upon said carrier, of a stopping device for the carrier, a trip on the arm and a controlling detent connected with the stopping means, the trip and detent being manually operable by the arm to engage the trip in one manner with the detent so that the trip is held against movement while the arm is being moved, and to move the trip in a different manner to shift the detent to thereby release the stopping means and permit the carrier to operate.

8. In graphophone mechanism, the combination with a record carrier and reproducer arm having a reproducer to traverse a record upon said carrier, a brake for the carrier to stop and start the same, and means operable by the reproducer instrumentalities to control both of said actions of the brake.

In testimony whereof I affix my signature.
EDWIN O. KLEMM.
